UNITED STATES PATENT OFFICE

167,871

INFLATABLE MATTRESS

Wilbur L. Vega, New Milford, N. J., assignor to
U. S. Fiber & Plastics Corp., Stirling, N. J.

Application May 5, 1952, Serial No. 19,587

Term of patent 14 years

(Cl. D5—2)

To all whom it may concern:

Be it known that I, Wilbur L. Vega, a citizen of the United States of America, residing in New Milford, in the county of Bergen and State of New Jersey, have invented a new, original, and ornamental Design for an Inflatable Mattress, of which the following is a specification, reference being had to the accompanying drawings, forming a part hereof.

Fig. 1 is a top plan view of an inflatable mattress showing my new design;

Fig. 2 is a bottom plan view of the inflatable mattress;

Fig. 3 is a side elevational view of the inflatable mattress; and

Fig. 4 is an end elevation of the inflatable mattress.

I claim:

The ornamental design for an inflatable mattress, as shown.

WILBUR L. VEGA.
